UNITED STATES PATENT OFFICE.

ARNE VICK, OF CHICAGO, ILLINOIS.

MITER-BOX.

SPECIFICATION forming part of Letters Patent No. 658,078, dated September 18, 1900.

Application filed December 28, 1899. Serial No. 741,817. (No model.)

To all whom it may concern:

Be it known that I, ARNE VICK, a citizen of the United States, residing at Chicago, in the county of Cook and State of Illinois, have invented certain new and useful Improvements in Miter-Boxes, of which the following is a specification.

The object of this invention is the production of an improved miter-box.

In the accompanying drawings, Figure 1 is a plan view of this miter-box, showing by dotted lines the saw in position, also showing in dotted lines the saw-carrying arm turned to its greatest angle. Fig. 2 is an under face view of the miter-box. Fig. 3 is a transverse vertical central section through the miter-box. Fig. 4 is a horizontal section through the central turn-table of the miter-box. Fig. 5 is an end elevation of the forward guide-blocks for the handle end of the saw. Fig. 6 is an under face view of the guide-blocks for the outer end of the saw.

Like letters of reference indicate corresponding parts throughout the several views.

In the construction of the miter-box I provide the supporting-frame A, having the sustaining-feet A' rigidly fixed to the frame, at the outer ends thereof, which feet are provided with the perforations A², by means of which the miter-box is secured to a bench or any other suitable means of support. The middle of the frame is provided with the opening A³ for the reception of a pivotal stud, and a dial-plate A⁴ is formed integral with said frame and concentric with the opening A³. Two bed-pieces B are secured to the upper face of the supporting-frame A, and the back pieces B' are secured to the bed-pieces B, said back pieces rising somewhat above the bed-pieces and forming a right angle with the bed-pieces B.

A saw-carrying arm C is located below the dial-plate and lies in contact with the under face thereof. A stud C', having an enlarged upper end, pivotally connects the saw-carrying arm C with the dial-plate A⁴, said stud passing through the opening A³ and also through a perforation in the saw-carrying arm C. This stud is of reduced diameter where it passes through said saw-carrying arm C and is screw-threaded at its lower end to receive a nut C². The saw-carrying arm

C is provided with the downwardly-extending ears C³, between which are pivoted the hand-lever C⁴, which lever bears at its forward end the integral stud C⁵, extending upward through an opening C⁶ in the saw-carrying arm and frictionally engaging the under side of the dial-plate A⁴. A flat spring is secured by means of the screw C⁷ to the under side of the saw-carrying arm C, its purpose being to hold the integral stud C⁵ in engagement with the under side of said dial-plate A⁴. When it is desirable to move the saw-carrying arm to change its angle with relation to the dial-plate A⁴, the lever C⁴ is raised by the fingers of the operator, and the stud C⁵ is withdrawn from its frictional engagement with the under face of the dial-plate A⁴.

D is a turn-table of circular outline mounted upon the stud C', and therefore being fixed with relation to the saw-carrying arm C. It is provided with an indicator D', intended to be placed into coincidence with figures upon the dial-plate A⁴ in order to indicate the angle at which the saw-carrying arm C stands with relation to the back pieces B'.

D² are two pairs of screw-threaded perforations in the saw-carrying arm C, and D³ are two similar perforations, which said perforations afford means for securing the guide-blocks, to be later described herein, rigidly to the upper face of the saw-carrying arm C.

D⁴ is a facing of wood or other suitable material for the turn-table D. It is provided with a diametric channel in its face, and this channel is filled with a tightly-fitting block of wood D⁵, held in position by the screw D⁶, passing through said facing D⁴ and engaging said block. This block is intended to be removed and replaced when after a considerable amount of use it has become worn by the contact of the teeth of the saw.

E are guide-blocks for the handle end of the saw-blade. Each is composed of a wedge-shaped piece of wood, and they are set slightly apart to leave a space between them for the passage of the saw-blade. A right-angled bracket E' holds said blocks rigidly in position and forms a means of adjustably connecting them with the saw-carrying arm C. This bracket is provided with the elongated openings E² in its base, and has the thumb-screws E³ for securing said bracket to the

saw-carrying arm. The two pairs of screw-threaded perforations D^3 provide means for a considerable adjustment of the guide-blocks to or from the turn-table D , and the transversely-elongated openings E^4 in the bracket E' provide for the adjustment of the blocks with relation to each other. A stop-block E^5 for receiving the saw is secured to the lower side of the guide-blocks E .

10. F are two similar guide-blocks secured rigidly to their supporting right-angled bracket F' and capable of a transverse adjustment with relation to each other for allowing more or less space between them for the support of the saw-blade. The base of the right-angled bracket F' is provided with the elongated openings F^2 for the reception of thumb-screws F^3 , intended to enter the screw-threaded perforations D^3 near the rear end of the saw-carrying arm C .

F^4 is a block rigidly secured to one of said guide-blocks F by the screw F^5 and having a slotted opening F^6 , providing an adjustable engagement between the other one of said blocks F and the securing-block F^4 . This block F^4 may be removed and renewed when worn by contact with the saw-teeth.

15. G are two stops, each having a pivotal connection with the under face of one of the upwardly-extending back pieces B' . The length of these stops is adjustable by means of the wood-screws G' , turned into their free ends. When a considerable number of pieces of molding are to be cut at a certain angle, the 20 stops G are arranged to limit the movement of the saw-carrying arm C . Those shown in Fig. 2 are represented as set to stop the saw-carrying arm at an angle of forty-five degrees with the length of the back pieces B' .

25. In operation this miter-box is secured to a bench or any other suitable means of support and a piece of molding placed upon the bed-pieces B and held firmly against the back pieces B' . A common crosscut-saw is inserted between the guide-blocks E and F and the saw and saw-carrying arm turned to the proper angle, which angle is determined by the indicator D' upon the dial-plate A^4 . The molding is sawed off upon the desired 30 angle, when the turn-table may be rotated to any other angle by raising the lever C^4 . The guide-blocks E and F may be adjusted with relation to each other and easily removed from their supporting-brackets E' and F' , respectively.

35. I claim as my invention—

1. In a miter-box, in combination, a supporting-frame; bed-pieces and back pieces on opposite ends of the supporting-frame, the 40 bed-pieces having a space between them; a

saw-carrying arm having a pivotal connection with said supporting-frame; a turn-table fixed with relation to said arm, and lying in the space between said bed-pieces, its surface being flush with the surfaces of said bed-pieces, which turn-table is adapted to rotate with the saw-carrying arm independently of the bed-pieces and back pieces; and means for forming a frictional engagement between the saw-carrying arm and the supporting-frame.

2. In a miter-box, in combination, a supporting-frame having a dial-plate; bed-pieces and back pieces for the frame; a saw-carrying arm having a pivotal connection with said frame concentric with the dial-plate; a turn-table fixed with relation to said arm; a lever pivotally mounted on said arm, having a frictional engagement with the supporting-frame; a spring for said lever; and means on the saw-carrying arm for supporting a saw.

3. In a miter-box, in combination, a supporting-frame; bed-pieces and back pieces on opposite ends of the supporting-frame, the bed-pieces having a space between them; a dial-plate on the supporting-frame, within said space between the bed-pieces; a saw-carrying arm having a pivotal connection with the frame; a turn-table fixed with relation to said saw-carrying arm, and lying over said dial-plate, within the space between said bed-pieces, which turn-table is adapted to rotate with the saw-carrying arm independently of the bed-pieces and back pieces, and has an indicator for said dial-plate; two brackets 95 having an adjustable connection with said saw-carrying arm; and guide-blocks on each of said brackets for receiving a saw.

4. In a miter-box, in combination, a supporting-frame having a dial-plate formed integral therewith; bed-pieces and back pieces for the frame, the bed-pieces being secured to said frame on opposite sides of the dial-plate; a saw-carrying arm; a turn-table over said dial-plate; a stud connecting the arm 100 and the turn-table rigidly together, which stud has a pivotal engagement with the supporting-frame; stops for limiting the pivotal movement of the saw-carrying arm; which turn-table is adapted to rotate with the saw-carrying arm independently of the bed-pieces and back pieces; two brackets having an adjustable connection with the saw-carrying arm; and guide-blocks on each of said brackets for supporting a saw between them.

ARNE VICK.
